ELECTRICAL CIRCUIT BREAKER

Oakley K. Beckler, Dallas, Tex., assignor, by
mesne assignments, of seventy-two and one-
half percent to Joseph H. Reynolds, Cisco, Tex.,
twenty-two and one-half percent to Marion H.
Rowe, and five percent to Jack A. Schley, both
of Dallas, Tex.

Application March 21, 1935, Serial No. 12,155

3 Claims. (Cl. 200—116)

This invention relates to new and useful im-
provements in electrical circuit breakers.

One object of the invention is to provide an
improved circuit breaker which is arranged to be
5 connected in an electrical circuit and which will
efficiently break the circuit in case of an over-
load or short circuit, being particularly adapted
for use in motor vehicles.

An important object of the invention is to pro-
10 vide an improved circuit breaker including a clip
formed of thermostatic metal, which is arranged
to engage two electrical contact points whereby
the electrical circuit is closed, the current flowing
through said clip; thus, an overload or short in
15 the circuit will act upon the clip to heat the
same, thereby causing an expansion thereof which
releases the clip from the contact points to break
the circuit, this breaking of the circuit permitting
the clip to cool and return to its normal
20 unexpanded position, whereby it may again be
engaged with the contacts to again close the
circuit.

Another object of the invention is to provide
25 an improved clip of thermostatic metal in a
circuit breaker, which is arranged to engage elec-
trical contacts to close a circuit, and means for
imparting a snap action to the disengagement of
said clip from said contacts when an overload
30 or short occurs in the circuit and expands the
clip, whereby a positive and quick breaking of
the circuit is had; said means also holding the
clip in a disengaged position until a manual op-
eration again engages the clip with the contacts.

A further object of the invention is to provide
35 an improved circuit breaker for the electrical
circuit of a motor vehicle, which may be used
indefinitely and which is cheap in manufacture
and simple in construction.

Still another object of the invention is to pro-
40 vide an improved circuit breaker, as described
above, which may be mounted in the usual clips
provided in the motor vehicles for the ordinary
glass tubular fuse now in general use.

A construction designed to carry out the in-
45 vention will be hereinafter described, together
with other features of the invention.

The invention will be more readily understood
from a reading of the following specification and
by reference to the accompanying drawing, in
50 which an example of the invention is shown, and
wherein:

Figure 1 is a side elevation of a circuit breaker,
constructed in accordance with the invention.

Figure 2 is a similar view, showing the clip in
55 its disengaged position.

Figure 3 is an elevation taken at right angles
to Figure 1.

Figure 4 is a transverse vertical sectional view
taken on the line 4—4 of Figure 1.

Figure 5 is a transverse vertical sectional view 5
taken on the line 5—5 of Figure 3.

Figure 6 is a horizontal cross-sectional view
taken on the line 6—6 of Figure 3.

Figure 7 is a view similar to Figure 6, showing
another form of spring for the clip, 10

Figure 8 is a side elevation of another form of
the invention.

Figure 9 is an elevation taken at right angles
to Figure 8.

Figure 10 is an elevation taken from the oppo- 15
site side to that shown in Figure 9.

Figure 11 is a transverse vertical sectional view
taken on the line 11—11 of Figure 9.

Figure 12 is a view similar to Figure 8, showing
the circuit breaker positioned within the usual 20
spring clips, and

Figure 13 is a horizontal cross-sectional view,
taken on the line 13—13 of Figure 9.

In the drawing, the numeral 10 designates a
support, which may be the rear side of the in- 25
strument panel of a motor vehicle, or other suit-
able place on which the circuit breaker 11 may
be mounted. The circuit breaker is connected
in the electrical circuit of the motor vehicle and

includes an elongated bar 12, which is preferably
30 made of bakelite, although it may be constructed
of any suitable electrical non-conducting mate-
rial. The bar has a pair of metal plates 13 dis-

posed along its inner side. The plates may be
35 constructed of copper or other electrical con-
ducting material and are substantially the same
width as the bar extending the length thereof,
being fastened thereto by rivets 14 and 14'.

The rivets are extended and pass through the support
40 to fasten the bar to the support 10. Suitable
insulating washers 10' are inserted between the
support and plates to insulate the support from
the latter.

The inner end of each plate is cut out at 45
so that when the plates are positioned on the
bar as shown in Figure 4, their inner ends will
lie parallel to each other with a space there-
between. It is pointed out that there is no elec- 50

trical connection between the plates. One of the
plates is connected by a wire A to one side of
the electrical circuit of the motor vehicle, while
the other plate is connected by a wire B to the
opposite side of the circuit. However, since there

55 is no connection between the plates, it is obvious
55

that electrical current can not pass from one plate to the other.

For closing the electrical circuit between the plates, a metal clip 16 is provided. This clip is 5 constructed of thermostatic metal, which is a fabrication of two metals having widely different coefficients of thermal expansion. When a metal 10 so formed is heated, it will bend away from the high expansive side, that is, if brass and steel are used in the construction of the metal, the heating thereof will cause the metal to bend away from the side on which the brass is located because there is an increased expansion of the brass with 15 relation to the steel. Thermostatic metal may be purchased on the open market and no claim is made to its particular qualities, the foregoing explanation being merely for the sake of clarity.

As clearly shown in Figures 1, 5 and 6, the thermostatic metal clip 16 is yoke-shaped and 20 straddles the central portion of the bar. The lower ends of the arms 16' of the yoke are crimped to form lugs 17, whereby when the clip is forced downwardly over the bar (Figure 6), the lugs will engage the underside of the plates 13. Since the 25 clip is located centrally of the bar 12, it is obvious that one of the arms 16' of the clip will engage the inner end of one of the plates 12, while the other arm will engage the inner end of the other plate, whereby the clip serves to electrically 30 connect the plates, thereby closing the circuit between the wires A and B.

A flat spring 18 (Figures 1, 2, 5 and 6) has one end secured to the outer face of the bar 12 by the rivet 14. A suitable insulating washer 19 surrounds the rivet 14, to insulate said rivet from the spring. The spring overlies the bar and extends to the central portion thereof, having its other end secured to the underside of the top of the yoke-shaped clip 16 by a rivet 20. A suitable 40 washer 21 of non-conductive material insulates the spring from the yoke. The rivet also serves to secure a thumb disk 22 of electrical non-conductive material to the outer end of the clip.

As clearly shown in Figures 1 and 2, the flat 45 spring is formed to exert its tension to force the yoke outwardly from the bar. The tension of this spring is slight, being only sufficient to move the ends of the arms of the yoke outwardly from the plates 12, when the lugs 17 disengage, as 50 shown in Figure 2.

It is pointed out that in forming the yoke-shaped clip 16, the arms 16' are positioned to snugly engage the sides of the bar 12. Therefore, when the clip is moved downwardly and the lugs 17 engage beneath the plates 12, the resiliency of the metal is sufficient to retain the lugs in engagement against the tension of the spring 18. Therefore, when the yoke is depressed to this position (Figure 6) the electrical circuit 60 between the wires A and B is closed, the current passing from one plate 12 to the other plate through the clip.

The thermostatic metal of which the yoke is constructed is made to carry a certain current. 65 Thus, whenever an overload or short occurs in the electrical circuit, the clip is heated. This heating causes an expansion of the clip. The metal having the greatest expansion of the two metals comprising the clip is located on the 70 inner side of said clip so that upon heating, the arms of the clip will bend outwardly, as shown by dotted line in Figure 6. As soon as these arms have bent sufficiently to permit the lugs 17 to clear the edges of the plates, the spring 18 will immediately move the clip outwardly to the

position shown in Figure 2, whereby the ends of the arms 16' of said clip are out of alignment with the plates. The spring 18 imparts a snap action to the disengagement of the clip from the plates. As soon as the arms move away from the plates due to the heating, as described, the electrical circuit is broken.

As soon as electricity ceases to pass through the clip, the metal therein will immediately cool and the arms 16' will move inwardly to their 10 normal position. This will cause said arms to engage the sides of the bar 12 when the thumb disk 22 is pressed. At this time, however, the electrical circuit is still broken because the spring 18 has moved the clip outwardly a sufficient distance to move the ends of the arms 16' of said clip out of alignment with the edge of the plate. The parts remain in this position until the operator depresses the disk 22 and clip secured thereto. This depression causes the lugs 17 to 20 again engage the inner side of the plates to again close the electrical circuit between said plates.

Since the life of the thermostatic metal is practically indefinite, it is obvious that a circuit breaker which will last during the life of the 25 vehicle to which it is attached, is provided. Since the voltage of the electrical circuit of a motor vehicle is comparatively low, the danger of arcing as the clip engages and disengages the plates is practically negligible. However, if there were 30 any tendency of arcing, the snap action in both engagement and disengagement of the arms 16' with the plates, would eliminate this. Although, I have shown the clip as connected with the flat spring 18, a coiled spring 25 (Figure 7) could 35 be employed. In such case the rivet 20 would be extended to slide through an opening 26 in the bar 12 and plate 13. The coiled spring surrounds the rivet being confined between the upper end of the clip and the bar, exerting its tension 40 upwardly at all times. The operation of the clip is the same.

In Figures 8 to 13, I have shown another form of the invention. This form is adapted to be used in the usual spring clips 27, which are 45 mounted on the inner side of the instrument panel 28 of a motor vehicle and which receive the usual glass tubular fuse. In constructing this form, a cylindrical body 30 of bakelite has two curved plates 31 mounted on its inner side 50 in the same way as the plates 13 are secured to the bar 12, that is, there is no electrical connection therebetween. The outer end of each plate, however, is constructed to completely encircle the ends of the body 30 so that when the 55 body is inserted into the clips, a good contact is made. Centrally of the body, the clip 16 is mounted in the same way as the form shown in Figure 7. This form may be used in the motor vehicles now on the market and since it operates in the same way as the form shown in Figures 1 to 6, a detailed description is deemed unnecessary.

It is obvious that a circuit breaker which is 60 simple in construction and cheap in manufacture is provided. Its operation is positive since it depends on the heating of the thermostatic clip, which will occur any time an overload or short occurs in the circuit. The snap action is an important 65 feature as it assures a positive make and break of the circuit, the one by pressing the thumb disk 22 and the other by the action of the bi-metal element. Although the breaker has been shown as used on the circuit of a motor vehicle, 70

It is obvious that it may be used where found desirable.

What I claim and desire to secure by Letters Patent is:

- 5 1. A circuit breaker including, an elongated body of non-conducting material, a pair of electrical contacts mounted on the body and having their inner ends extending in parallel spaced relationship at the central portion of the body, a
  - 10 unitary bi-metallic circuit closing element operable in one direction to move into gripping engagement with the contacts to close the electrical circuit therebetween, and a spring element secured to the bi-metallic element and adapted to
  - 15 be placed under tension when said bi-metallic element is in circuit closing position, whereby said spring element effects an immediate disengagement of the bi-metallic element from the contacts when said bi-metallic element is over-heated due to an overload or short circuit.
  - 20 2. A circuit breaker including, an elongated body of electrical non-conducting material, a pair of electrical contacts mounted on the body and having their inner ends extending in parallel re-
  - 25 lation one on each side of an intermediate por-
- tion of said body, a yoke-shaped bi-metallic clip straddling the inner ends of the contacts for engaging said contacts to close an electrical circuit therebetween, the spacing between the yoke arms being such that said arms normally frictionally grip the contacts, and spring means engaging the yoke for effecting a disengagement of the yoke arms from the contacts and operable when the clip is heated due to an overload or short circuit.
3. A circuit breaker including, a cylindrical 10 body of electrical non-conducting material insertable in cartridge gripping spring clips, a pair of electrical contacts on said body with their outer ends engaging within said clips, and their ends extending in parallel spaced relationship at 15 an intermediate portion of the body, a bi-metallic yoke having its arms spaced from each other so as to frictionally engage and grip said contacts to close the circuit therebetween, and spring-actuated resettable means engaging the 20 yoke for disengaging the arms of said yoke from the contacts to break the circuit when the yoke is heated due to an overload or short circuit.

OAKLEY K. BECKLER. 25
